UNITED STATES PATENT OFFICE.

JAMES HARVEY LEONARD, OF EAST ORANGE, NEW JERSEY, ASSIGNOR TO JENKINS
MANUFACTURING CO., OF NEW YORK, N. Y., A CORPORATION OF NEW YORK.

WATER-CLOSET.

1,157,989.

Specification of Letters Patent.

Patented Oct. 26, 1915.

Application filed February 15, 1915. Serial No. 3,191.

To all whom it may concern:

Be it known that I, JAMES H. LEONARD, a citizen of the United States, residing in East Orange, Essex county, State of New Jersey, have invented certain new and useful Improvements in Water-Closets, of which the following is a specification, reference being had to the accompanying drawings, forming a part hereof.

10 This invention relates to water closets generally but will find an especial range of usefulness in connection with closets intended for marine use.

It has for its object to improve the construction of such closets by providing an improved check valve or gate valve for preventing the water from backing up into the bowl and preventing the return from the discharge pipe of foul air.

20 The invention is also concerned with the provision of an improved housing for the valve referred to, which is constructed with especial reference to the bowl in which it is to be used so that the housing with the 25 valve may be readily inserted in the bowl or withdrawn therefrom for purposes of replacement, repair or cleaning. The exposed portion of the valve housing may be ornate in character so that the general sightliness 30 of the bowl will not be marred.

The invention will be described with particular reference to the accompanying drawings in which is illustrated, by way of example, one embodiment thereof.

35 In the drawings—Figure 1 is a view in side elevation of a bowl having associated therewith a valve housing and a valve embodying the present improvements. Fig. 2 is a view in vertical section of the bowl 40 shown in Fig. 1 and disclosing particularly the position of the valve with respect to the discharge pipe. Fig. 3 is a fragmentary view in section taken on the plane indicated by the line 3—3 of Fig. 2, looking in the 45 direction of the arrows, and showing particularly the valve housing and the means for securing the same in place.

The bowl *a* is of known type and is formed with the usual lower leg *a'* communicating 50 with the discharge *a''*. A section of the bowl at its lower portion may be cut away on one side, as indicated by the line *a'''* of Fig. 3, to permit the insert of the improved valve housing *b* in which is mounted a gate valve *c*

as on a transverse pintle *c'* carried by the 55 housing. The bowl *a* is so recessed, transversely and longitudinally as to insure a snug sliding fit of the valve housing throughout. Thus, the lower leg *a'* may be recessed as at *a''''* to receive snugly and guide, the base 60 *b'* of the valve housing. Transversely, the housing is of the same outline as the interior of the leg *a'* (cylindrical) so as to form, when in position, a perfect continuation of the discharge passages of the bowl. The 65 housing may be retained in fixed position by means of a bolt *d* which passes through the base *b'* of the housing and is in threaded engagement with a correspondingly threaded insert *e* of lead or other suitable material, 70 which is placed permanently in a recess in the bowl *a*. Of course, the latter will usually be of porcelain. The valve housing may be closed to view by means of a plate *f*, the exposed face of which may be ornate, this plate 75 being of such form and dimension as to fit snugly within the recess formed in the side of the bowl *a* and being pressed into gas-tight engagement therewith by means of a bolt *g* which passes through the plate and is 80 threaded into the side of the valve housing. The tightness of the connection may be insured by placing suitable packing such as *i* and *k* between the plate and the bowl and between the head of the bolt *g* and the plate, 85 respectively, as will be evident. By the gas-tight union of the plate with the recess danger of foul gases escaping from the connections within the recess, is eliminated.

The gate valve *c* performs its usual function in that it automatically seats after flushing and prevents water from backing up into the bowl and the return of foul gases thereto. The valve *c* may, of course, be faced with a yielding gasket *c''* to insure a gas-tight connection between the valve and its seat.

When desired, the valve housing *b* with the valve *c* may be removed bodily for purposes of repair, replacement, or cleaning, by 100 loosening the bolt *g* and removing the plate *f* so as to afford ready access to the retaining bolt *d*, the removal of which permits the valve housing to be withdrawn readily from the bowl *a*.

105 While the invention is not to be limited to the character of the material employed in the valve and the valve housing it has been

found that gun metal possesses those properties which commend it highly to use under the conditions encountered.

Changes in the form and arrangement of the elements described may be made without departing from the spirit of this invention provided such changes fall within the scope of the appended claim.

I claim as my invention:—

19 In a water closet, in combination with the bowl having a lower leg communicating with the discharge outlet, and having a recess formed in the side thereof across said lower leg, a valve housing of similar cross-sectional dimension and outlet to the passage in said lower leg and having a snug sliding fit with said recess, a flat valve pivoted on the hous-

ing and controlling the passage therethrough, securing devices for the valve housing, means carried by the bowl to receive said securing devices, a plate to close said recess in the bowl, a bolt passing through the plate and engaging the housing to maintain the plate in position, and packing coöperating with the plate and the bolt to insure a gas-tight closure of the recess, said housing and valve being removable bodily from the recess from the exterior of the bowl.

This specification signed and witnessed this 13th day of February, A. D., 1915.

JAMES HARVEY LEONARD.

Signed in the presence of—

F. KELBLY,
PAUL TURNER.
